Assistant Examiner — Caitlin A Laverty

CLAIM

The ornamental design for a medicine cabinet as shown and described.

DESCRIPTION

FIG. 1 is a top perspective view of a medicine cabinet showing my new design;

FIG. 2 is another top perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof;

FIG. 9 is an enlarged partial view of portion 9 taken from FIG. 1;

FIG. 10 is an enlarged partial view of portion 10 taken from FIG. 2; and,

FIG. 11 is an enlarged partial view of portion 11 taken from FIG. 7.

The broken lines illustrate portions of the medicine cabinet that form no part of the claimed design.

The short dash-long dash broken lines depict the boundary of the enlarged portions and form no part of the claimed design.

1 Claim, 11 Drawing Sheets
